UNITED STATES PATENT OFFICE

147,038

DESIGN FOR A BOAT LUGGAGE TRAILER

Walter O. Foster, Los Angeles, Calif.

Application January 19, 1946, Serial No. 125,740

Term of patent 3½ years

(Cl. D14—3)

To all whom it may concern:

Be it known that I, Walter O. Foster, a citizen of the United States of America, residing at Los Angeles, Los Angeles County, State of California, have invented a new, original, and ornamental Design for Boat Luggage Trailers, of which the following is a specification, reference being had to the accompanying drawing, forming a part thereof.

Fig. 1 is a plan view of a boat luggage trailer, showing my new design.

Fig. 2 is a side elevational view and

Fig. 3 is a front end view.

I claim:

The ornamental design for a boat luggage trailer, as shown.

WALTER O. FOSTER.
